MEANS FOR PRODUCING SUPERHEATED VAPOR

Walter Engel, Neuss (Rhine), Germany, assignor to Sulzer Freres, Societe Anonyme, Winterthur, Switzerland, a corporation of Switzerland

Application December 16, 1954, Serial No. 475,682

2 Claims. (Cl. 122—382)

The present invention relates to forced flow steam or vapor generators of the once-through type, in which the steam or vapor is generated at critical or supercritical pressure.

In forced flow steam or vapor generators in which the working medium is converted from the liquid phase to the vapor phase at critical or supercritical pressure, no boiling of the liquid occurs, and irregularities which are caused by boiling phenomena are avoided. When generating steam or vapor above the critical pressure, the feed water or liquid medium is subjected to a pressure which is at least equal to the critical pressure. If the liquid is heated at this pressure up to the critical temperature, the liquid is transformed into vapor without any clearly defined change of phase such as boiling when operating at subcritical pressures. If additional heat is supplied, the vapor is immediately superheated.

In conventional forced flow generators in which vapor or steam is generated in this manner and in which heat is transmitted to the operating medium in a first part by radiation, and in a second part by contact of hot combustion gases with boiler tubes, the zone in which the liquid is converted into vapor is usually arranged in the combustion chamber. Here, however, the heat is transmitted by radiation and is too great, since only a relatively small amount of heat is necessary for converting a liquid into vapor at supercritical pressure. It has been proposed to place the conversion zone of the heating surface into the region in which the heating is effected by contact with the hot furnace gases, and to arrange the heating surface in which the vapor is superheated in the combustion chamber. In this case, however, the superheater tubes which are exposed to radiation are subjected to high heat stresses which may cause difficulties.

These difficulties are avoided by the present invention, according to which the liquid is heated by radiant heat to a temperature below the critical temperature and is converted into vapor by heat exchange with superheated vapor in a heat exchanger which is arranged outside of the flow of the combustion gases and which is not exposed to radiant heat. The vapor thus produced is superheated by radiant heat and/or by heat transfer from combustion gases by convection and is used for heating the heat exchanger in which the liquid is converted into vapor. The heating vapor leaving the heat exchanger is once more superheated by the combustion of fuel and by heat transfer by radiation and/or convection.

According to the invention, a continuous stream of liquid operating medium is continuously converted into vapor and is immediately superheated to the desired temperature at which the vapor is used.

In a modification of the apparatus according to the invention, the operating medium which has received some heat from superheated vapor in the heat exchanger in which the liquid operating medium is converted into vapor, is cooled by indirect heat transfer to liquid operating medium which is on its way to the generator. This

2

cooling causes reconversion of all or part of the generated vapor into liquid, affording blowing down of liquid containing salts and impurities. Only the heat in the blown down liquid is lost, the heat transferred into the cooling liquid merely raising the temperature of the liquid which is fed into the generator.

In the heat exchanger in which the liquid is heated by superheated vapor and itself converted into vapor, the superheated heating vapor may be conducted inside the 10 heating tubes and the liquid and vapor produced therefrom may be outside of the tubes, affording easy cleaning of the heat exchanger, since the only part of the steam generating apparatus according to the invention where scale may be formed is the conversion zone, i. e. 15 the zone in which the liquid is transformed into vapor.

The tubes in the heat exchanger carrying the superheated heating vapor may be arranged within tubes of larger cross section which carry the liquid to be converted into vapor.

20 For cooling the operating medium passing through the heat exchanger, the medium may be conducted outside of the heat exchanger into an indirect cooler through which liquid operating medium is conducted prior to being fed into a preheater which may be heated by combustion 25 gases of the generator. The cooler may be arranged in parallel relation to the feed line for the generator, so that the portion of the liquid to be fed into the generator which passes through the cooler can be adjusted. In that case a valve is preferably provided at the inlet of the cooling 30 liquid into the cooler, a second valve being provided in the portion of the feed line by-passing the cooler, so that either a part of the liquid operating medium, or all of it, can be passed through the cooler, or no liquid operating medium can be passed through the cooler prior to being 35 fed into the generator.

With the system according to the invention, the working medium can be cooled and liquid containing salts and impurities can be blown down in desired amounts without interrupting the circulation of the working medium through the generator and without interrupting vapor generation.

The terms "liquid" and "vapor" used in the present specification and in the claims include water and steam. Where the words "water" and "steam" are used, these 45 include substances in liquid and vapor state other than water and steam.

The novel features which are considered characteristic of the invention are set forth with particularity in the appended claims. The invention itself however and additional objects and advantages thereof will best be understood from the following description of embodiments thereof when read in conjunction with the accompanying drawing, in which

55 Fig. 1 is a diagrammatic illustration of a vapor generator according to the invention;

Fig. 2 is a diagrammatic illustration of a modified vapor generator according to the invention, comprising cooling means interposed in the conversion zone;

60 Fig. 3 illustrates a modified portion of the vapor generator shown in Fig. 1.

The same numerals designate the same parts in all figures.

In the forced flow once-through vapor generator shown 65 in Fig. 1, the liquid working medium is fed, at least at the critical pressure of the medium, into a preheater 2 which is situated in a flue gas duct 1. From the preheater 2, the liquid flows into a heater 4 which is disposed in a combustion chamber 3, for receiving heat substantially by radiation. The liquid operating medium leaves the heater 4 at a temperature below the critical 70 temperature of the medium. Thereupon the liquid passes

through a tube 6 disposed in a special heating chamber 5' of a heat exchanger 5, in which the working medium is converted from the liquid into the vapor or gas phase. If the working medium is water, it may enter the tube 6, for example at 370° C., and leave the tube 6 in the form of steam of, for example, 380° C. This steam flows into a superheater 7 adapted to receive heat substantially by radiation in the chamber 3. The superheated steam is conducted in counter-flow to the medium to be converted into steam through the heating chamber 5' for heating the tube 6. Thereby the superheated steam loses a part of its heat content, which is restored to it in a superheater 8 arranged in the radiant heat chamber 3. The steam is further superheated in another superheater 9 which receives heat by contact with the combustion gases.

The tube 6 in which the liquid is converted into vapor is situated outside of the radiant heat chamber 3 and is also out of contact with the flue gases, the tube 6 being heated indirectly by superheated steam from the same system without being exposed to radiant or convection heat resulting from the combustion of fuel.

In the vapor generator shown in Fig. 2, the system of steam generation employed is similar to that of Fig. 1. In addition, however, the tube 6 is provided with a section 10 of enlarged cross section which is not heated by superheated steam. The medium flowing through this enlarged section is cooled for reconversion into liquid form to afford blowing down of liquid containing salts through a blow-down pipe 11. The cooling of the working medium which is conducted through the enlarged tube section 10 is effected by using liquid working medium flowing to the preheater 2 as a cooling agent. This cooling liquid is taken from a feed pipe 12 and is conducted into a tube placed within the enlarged tube section 10 by means of an inlet pipe 13. The cooling liquid flows from the cooler 10 through an outlet pipe 14 and a connecting pipe 15 into the preheater 2. Valves 17 and 18 are provided, respectively, in the inlet pipe 13 and in a pipe 16 by-passing the cooler 10.

If all of the liquid required for feeding the vapor generator is used as cooling medium, the valve 17 is opened and the valve 18 is closed. If only some of the liquid is to be used as cooling agent for the cooler 10, the valves 17 and 18 are correspondingly adjusted and the liquid not required for cooling flows directly through the by-pass pipe 16 into the connecting pipe 15. When no blowing-down is needed, the valve 17 is closed and the entire liquid stream flows through the by-pass pipe 16 and through the connecting pipe 15 into the preheater 2.

Instead of conducting the liquid to be converted into

vapor in the heat exchanger 5 inside of a tube 6 and passing the superheated vapor for heating the tube 6 outside of the latter, the superheated vapor may be conducted through a conduit 5" and the medium to be heated 5 may be passed in counter-flow relation through a conduit 6' which surrounds the conduit 5". This is shown in Fig. 3.

While specific embodiments of the invention have been shown and described, it will be apparent to those skilled in the art that various changes, modifications, substitutions, additions and omissions may be made therein without departing from the spirit and scope of the invention as set forth in the appended claims.

What is claimed is:

1. An apparatus for producing superheated vapor of at least critical pressure from a liquid operating medium comprising a furnace for burning fuel, a heating tube system heated by combustion gas from said furnace, means for forcing the liquid operating medium through said tube system at least at the critical pressure of the operating medium, an indirect superheated vapor heated heat exchanger including a tubular conduit connected with said heating tube system for receiving heated liquid operating medium therefrom for converting the liquid operating medium into vapor, a superheater tube system heated by combustion gas from said furnace and connected with said tubular conduit for receiving vapor produced in said heat exchanger, a cooler interposed in said tubular conduit, a blow-down means connected with said cooler for removing liquid operating medium from the medium flowing through said cooler, said heat exchanger being connected with said superheater tube system for receiving superheated vapor as heating agent therefrom, and a superheater connected with said heat exchanger for receiving and resuperheating the vapor which has served as heating agent in said heat exchanger.

2. An apparatus according to claim 1 including a feed pipe for said heating tube system, said cooler including a conduit connected with and by-passing a portion of said feed pipe for conducting liquid operating medium as cooling agent through said cooler.
